CLAIM

The ornamental design for a module clamp, as shown and described.

DESCRIPTION

FIG. 1 is an upper perspective view of a module clamp;
FIG. 2 is a lower perspective view of the module clamp
shown in FIG. 1;

FIG. 3 is a left-side view of the module clamp shown in FIG.
1;

FIG. 4 is a right-side view of the module clamp shown in
FIG. 1;

FIG. 5 is a front view of the module clamp shown in FIG.
1;

FIG. 6 is a rear view of the module clamp shown in FIG. 1;
FIG. 7 is a top view of the module clamp shown in FIG. 1;
and,

FIG. 8 is a bottom view of the module clamp shown in FIG.
1.

The broken lines depict portions of the module clamp that
form no part of the claimed design.
